UNITED STATES PATENT OFFICE

2,059,135

DISPENSING DEVICE

Andrew S. Moe, Austin, Minn.

Application January 27, 1936, Serial No. 61,092

5 Claims. (Cl. 221—106)

This invention relates to an apparatus for dispensing bulk goods, such as coffee, rice, tea, sugar, dry beans, pop-corn, etc., in measured quantities, and has for its object to provide, in a manner as hereinafter set forth, an apparatus of the class referred to including means for adjusting the amount of the contents thereof which is to be dispensed.

A further object of the invention resides in the providing, in a manner as hereinafter set forth, a dispensing apparatus for the purpose referred to including a hopper, a support for hopper, said hopper being formed with an open top and a controllable open bottom, said hopper and said support having coacting means for connecting them together and for permitting the hopper to tilt relatively to the support and said support including means to constitute a closure for the open upper end of the hopper when the latter is disposed in parallel relation to the support.

A further object of the invention is to provide, in a manner as hereinafter set forth, an apparatus for the purpose referred to including a tiltable hopper and a support for the latter, said hopper being formed with an open top and capable when tilted from the support of being filled from its open top, and with support having means for closing the open top of a hopper when the latter is in non-tilted position.

A further object of the invention is to provide, in a manner as hereinafter set forth, a dispensing apparatus for the purpose referred to including an adjustable material dispensing unit having means for adjusting the quantity of the contents of the apparatus which is to be discharged from the latter.

Further objects of the invention are to provide, in a manner as hereinafter set forth, an apparatus for the purpose referred to which is simple in its construction and arrangement, strong, durable, compact, thoroughly efficient for the use intended thereby, readily adjusted, pleasing and distinctive in appearance, conveniently operated for dispensing purposes, and comparatively inexpensive to manufacture.

With the foregoing and other objects which may hereinafter appear, invention consists of the novel construction, combination and arrangement of parts as will be more specifically described and are as illustrated in the accompanying drawing wherein is shown the preferred embodiment of the invention, but it is to be understood that changes, variations, and modifications may be resorted to which fall within the scope of the invention as claimed.

In the drawing:

Figure 1 is a front elevation of the apparatus,

Figure 2 is a vertical sectional view of the apparatus illustrating in dotted lines the hopper element tilted and opened, in full lines the hopper element closed and in dotted lines the closure for the hopper element shifted to opened position, 5

Figure 3 is a fragmentary view in rear elevation of the apparatus,

Figure 4 is a fragmentary view in longitudinal 10 section illustrating the dispensing unit of the apparatus, and

Figure 5 is a fragmentary view in transverse section illustrating the dispensing unit in full lines in closed position and in dotted lines in dispensing position.

The apparatus includes a hopper element 6 formed of a front 7, sides 8, a back 9, and a depending inverted pyramidal bottom 10 open, as at 11 at its lower end to form an outlet. The element 6 is open at its top. The front 7 of element 6 is formed of a U-shaped portion 12 having positioned against the inner face thereof a transparent panel 13 which extends from the lower end to the upper end of front 7 and is 25 suitably secured against the inner face of the portion 12. The element 6 is substantially of oblong contour and is disposed on its lower end or bottom. Secured to the outer face of the back 9 of the element 6, by the hold-fast devices 14 is 30 a vertically disposed yoke 15 having its sides arranged adjacent to the sides 8 of said element 6. Formed integral with the bottom of the yoke 15 and offset with respect to the ends of said bottom are depending rearwardly directed angle-shaped 35 coupling tongues 16 which are employed for a purpose to be referred to.

The apparatus includes a support element 17 for suspending the element 6 and also for supporting a container, not shown for receiving the 40 material dispensed from element 6. The element 17 is formed of two sections 18, 19. The section 18 is vertically disposed and the section 19 extends forwardly at right angles to the lower end of the section 18. The latter is of 45 materially greater length than that of section 19. The section 18 is in the form of an elongated yoke. The section 19 is in the form of a yoke having its sides, at its open end merging into the bottom of the section 18. The sections 18, 50 19 are of the same width. The sides of the section 18 are indicated at 20, 21 and each of which has its upper end inturned to provide a loop 22. Mounted in the loops 22 is a pivot bar 23. The section 18 of the element 17 is of materially 55

greater length than the element 6. The section 17 includes a closure or lid 24 for the open upper end of the element 6. The closure 24 is flanged at its front and at its sides and at its rear is provided with a barrel 25 through which extends the bar 23. The flanged front of the closure 24 is indicated at 26 and which has secured to its outer face, by the hold-fast devices 27 an upstanding handle member 28. The sides 20, 21 of the section 18 between the transverse medians and lower ends thereof are formed with aligning rearwardly directed lugs 29 to which a holder rod 30 is secured. The rod 30 is disposed transversely relative to element 17 and is adapted to have seat thereon and depend from the rear sides thereof the tongues 16 whereby the element 6 is connected to the section 18 of element 17 at a point the required distance above the section 19. The tongue 16 and rod 30 coact to provide a tilting connection for the element 6 relative to the element 17. The tilting of the element 6 in this connection is forwardly and downwardly relative to section 18 of element 17. The tongue 16 and rod 30 coact to provide a means for suspending the element 6 forwardly of the section 18 of the element 17. The outer sides of the tongues 16 are arranged to oppose the inner faces of lugs 29. When the element 6 is vertically disposed, in a manner as shown in Figure 2, the yoke 15 is positioned between the sides 20, 21 and are spaced from said sides.

The apparatus includes a dispensing unit 31 formed of a pair of oppositely disposed outwardly directed upwardly inclined spaced rectangular plates 32 secured against the lower faces of the sides 33, 34 of the bottom 10 by the hold-fast means 35. Formed integral with the bottom edges of the plates 32 are spaced parallel depending annular supporting members 36. Supported by the members 36 is a stationary cylinder 37 formed lengthwise thereof with a pair of diametrically disposed slots 38, 39, the former constituting an intake for cylinder 37 and the latter an outlet for cylinder 37. Fixedly secured in one end of the cylinder 37 is a closure head 40 having an axially arranged opening 41. The wall of opening 41 is threaded. Slidably mounted in the other end of the cylinder 37 is a head member 42 of circular cross-section and which provides for closing the other end of cylinder 37. The head member 42 coacts with the head member 40 for measuring the quantity of the contents of the element 6 which is to be discharged. The head member 42 coacts with the head member 40 for increasing or decreasing the area of that portion of the cylinder 37 which receives the portion of the contents of element 6 to be discharged. The head member 42 has a peripheral flange 43 on its inner end, a peripheral flange 44 coacting with the flange 43 to provide a peripheral groove 45 and a peripheral flange 46 at its outer end which is of greater diameter than the flanges 43, 44 and coacts with an end edge of cylinder 37 to constitute a stop for the inward shifting of member 42 within the cylinder 37. The head member 42 is adjusted to and from the head member 40 by a bar 47 which is secured at one end to the inner end of head member 42, and extends through the opening 41. The bar 47 is provided with peripheral threads 48 for thread engagement with the threaded wall of the opening 41, a stop 49 which coacts with the head 40 for limiting the inward shift of the bar 47 and a handle piece 50 on its outer end to facilitate the revolving of the bar.

Mounted in the groove 45 of the head member 42 is an annular resilient gasket 51 which engages the inner face of cylinder 37. The latter extends into the bottom 10 of the element 6 through the opening 11. Revolubly mounted upon the cylinder 37 and confined between the members 36 is a sleeve 52 formed with a discharge spout 53 and a slot 54 disposed at right angles to the spout 53 for registry with the slot 38 in cylinder 37 for the purpose of establishing communication between the interior of the cylinder 37 and the element 6. The sleeve 52 controls the intake to cylinder 37. The spout 53 controls the discharge from cylinder 37. The sleeve 52 extends into the element 6 through the opening 11.

When material is to be dispensed from the element 6 the sleeve 52 is shifted to bring the slot 54 into registry with slot 38 and also for the purpose of closing slot 39 and when the sleeve 52 is in such a position the spout 53 is disposed at right angles to the slots 38, 39. After the cylinder 37 has been filled with the material to be dispensed, the sleeve 52 is shifted to close the slot 38, such as shown in Figure 2 and with the slot 54 closed by cylinder 37. When slot 38 is closed by sleeve 52 the spout 53 will be shifted to the position shown in Figure 2 whereby slot 39 will be opened and the material discharged from cylinder 37 into the spout 53. To again fill cylinder 37 it will be necessary to shift the sleeve 52 to the position shown in Figure 5.

The closure 24 when in closing position with respect to the element 6 couples the latter with the element 17 in the position as shown in full lines in Figure 2 and prevents the tilting of element 6. When the closure 24 is shifted upwardly to opened position it permits the element 6 to assume the dotted line position shown in Figure 2 and when in such position the element 6 may be supplied with any suitable material from its open upper end.

What I claim is:

1. In a dispensing apparatus a supporting element including a vertical section, an open top hopper-like material container element at the front of the said section, a dispensing unit at the bottom of the container element, said container element and vertical section having inherent superimposed coacting parts to provide for the suspension and tilting of the container element relative to the supporting element, and said supporting element including a shiftable combined closure and retainer hinged at its rear to said section for engaging with the container element to close its open upper end when non-tilted and for detachably retaining the container element in non-tilted position.

2. In a dispensing apparatus an upstanding supporting element having a rod disposed transversely of and intermediate its ends, an open top hopper-like material container element having depending inverted L-shaped spaced parallel parts near the lower end of its back for fulcruming on said bar to provide a suspension for and to permit of the container element tilting forwardly relative to the supporting element, and said supporting element including a shiftable part hinged at its rear for engaging with the container element to close its open upper end and for detachably retaining the container element in non-tilted position.

3. In a dispensing apparatus, an open top hopper-like material container structure, a support formed of a vertical and a horizontal section ex-

tending forwardly at right angles to the lower end of the vertical section, said horizontal section providing a base for the support, said structure arranged over said horizontal section and forwardly of said vertical section, said support being provided at the upper end of said vertical section with a forwardly extending hinged closure for the open top of said structure, said closure when in closing position for said structure 5 maintaining the latter parallel to said vertical section, and said structure and vertical section having coacting superimposed parts for suspending the structure over and above said horizontal section and to provide for the tilting of said 10 structure relative to said vertical section when the hinged closure is free of said structure.

4. In a dispensing apparatus an open top upstanding hopper-like material container structure provided at its rear and in proximity to its 20 bottom with a pair of spaced depending inverted L-shaped rearwardly offset tongues, and a skeleton support including a vertical section formed transversely thereof with a rod, said tongues being shiftably mounted in superimposed relations 25 on said rod and depending therefrom, said tongues and bar coacting to suspend said structure from said support and provide for the tilting of said structure relative to said support, and

said support including a closure hinged at its rear to the upper end of said section and capable of engaging with said structure for closing the open top of the latter and when engaged with the structure detachably retaining it in non-tilted position.

5. In a dispensing apparatus an open top upstanding hopper-like material containing structure having controllable dispensing means at its lower end, a supporting element including an upstanding skeleton hanger section and a forwardly extending base section, said hanger section being formed of a pair of vertical, spaced parallel side members free of connection to each other at their upper ends, a shiftable closure for the open top of said structure, a pivot supported by and at the upper ends of said members, said closure having means at its rear for shiftably connecting it to said pivot, said members and structure having superimposed coacting parts for suspending the structure over and spaced above said base section and to provide for the tilting of said structure relative to said hanger section, and said closure when in closing position relative to the open top of said structure preventing the tilting of the latter relative to the hanger section. 10 15 20 25
